UNITED STATES PATENT OFFICE.

PHILIP A. JACKSON, OF DAYTON, OHIO, ASSIGNOR TO THE EGRY REGISTER COMPANY, OF DAYTON, OHIO, A CORPORATION OF OHIO.

AUTOGRAPHIC REGISTER.

Application filed December 26, 1924. Serial No. 758,074.

My invention relates to autographic registers.

It is the object of my invention to provide an autographic register in which a plurality of sheets may be fed out of the register and a record sheet kept in the register, the several sheets being fed in alignment.

It is the object of my invention to provide an autographic register in which the sheets are constantly maintained in alignment and are fed to the writing table in aligned condition.

It is a further object to provide means for ejecting the sheet and means for delivering the sheets to the writing table so that all the ejecting means has to do is to pull that portion of the sheet which is on the writing table out of the machine. Heretofore it has been necessary for the ejecting means to pull the entire length of sheets from the supply rolls which put such a strain upon the sheets and ejecting mechanism that the several sheets were either pulled out of alignment or torn where they engage the ejecting means.

It is an additional object of my invention to provide a register in which there shall be the minimum of perforations in the sheets, there being two perforations between the tickets. It is preferred to have such perforations as those ordinarily used for mounting the tickets in loose leaf binders. Thus it is my object to provide a machine which will handle sheets without additional perforations and with the perforations relatively remote from the side of the paper, thus effecting a saving both in production of the paper, machinery required and a great ease in handling, as ordinary perforated paper has a serious objection in that it is easily torn and the several sheets catch on one another and the carbon paper which is arranged transversely of autographic registers.

It is a further object to provide means of always keeping the paper in engagement with the aligning means as it is taken directly from the supply rolls.

It is a further object to provide an aligning means which is in contact with the paper over a long area so that the paper may be withdrawn from the supply rolls with the minimum of strain on the paper and with the least likelihood of tearing.

It is a further object to provide large blunt pins of suitable diameter having broad bearing surfaces in engagement with the large punched holes in the sheets so that there will be minimum of tearing of the paper, if any.

It is an additional object of my invention to provide a machine in which the operating handle may be reciprocated and the bill can not be ejected until the handle makes a complete reciprocation.

It is a further object to provide a paper feeding means which is in the nature of a double delivery feed by which the paper is pushed on the table rather than the paper is pulled off of the table, as hereinbefore common in paper handling means in autographic registers, directly from the rolls.

It is a further object to provide a machine which, if it becomes necessary, may be reversed in direction without having the sheets get out of alignment.

It is a further object to provide the surface of the rollers which carry the bills out of the register with a speed of travel faster than the travel of the bills so that the paper is kept taut and smooth. This is possible since the rollers are not gripped tightly together and they may travel faster than the bills. This is a feature of importance because it is mechanically impossible to make two sets of gripper rollers or one set of gripper rollers and delivery mechanism to synchronize perfectly. Thus it eliminates the necessity of great perfection in gearing and other mechanism which would make an autographic register expensive. This also provides means for constantly adjusting the pull on the bills despite the conditions of temperature and humidity which may affect the paper; the pull is not sufficient to injure the bills but simply enough to keep them taut so that they are delivered out of the register.

It is a further object of my invention to provide means by which the pins enter gradually into the papers in the bills and as the papers are driven under the belts or chains carrying the pins, the pins are forced downwardly through the apertures in the webs, forcing the walls of the perforations in the webs into superimposed alignment. This operation takes place gradually and progres-

sively with the minimum of strain upon the paper.

It is a further object to thus bring the webs of paper in alignment laterally as well as longitudinally of the paper. It is a further object of my invention to take care of slight variations in lengths of the bills by the tapered pins.

It is a further object to provide a greater space between the paper guides and the belt at the point where the pins first start to enter the paper webs than later in the point of engagement between the webs and pins so that at the point of first engagement of the pins with the holes in the webs, the webs will be freer from binding due to the friction under the belt and they may shift sufficiently to effect the alignment. Thus the assembly and aligning of the bills on the sheets or webs is done before passing around the pulley where they are permanently bound together.

It is an object to provide tapered guides for holding the paper in position relative to the driving rollers, belts and pins.

It is an additional object to provide ready means of loading my register by which it is possible to load a separate carriage or frame outside of the register with the paper aligned and positioned so that when the loaded frame is placed in the machine the driving pins will enter the perforations in the paper webs and move the webs of paper into the operative position with respect to the rollers and writing table.

Referring to the drawings:

Figure 1 is a side elevation of the complete machine with the side wall removed showing certain supporting members in section, the writing table in section and the cover in section, as well as the frame. I thus disclose the entire scheme of arrangement of the register;

Figure 2 is a perspective of the writing table and the slotted approach table;

Figure 3 is a section on the line 3—3 of Figure 1;

Figure 4 is a detail section showing the aligning mechanism of the loading frame in position;

Figure 5 is a detail of one corner of the frame showing it in its down position before it is fully moved into its home position;

Figure 6 is an enlarged view of the front of the loading frame;

Figure 7 is a plan view of the machine with the cover removed and the writing plate removed;

Figure 8 is a detail elevation, partially in section, of the ejecting rollers with several sheets therebetween;

Figure 9 is a section on the line 9—9 of Figure 8;

Figure 10 is a detail of the master actu-

ating segment and the ratchet and cam mechanism for preventing the ejecting of a portion of a bill;

Figure 11 is a plan view of the machine with the interior mechanism removed showing the arrangement of the loading frame as it appears when it is withdrawn from the machine;

Figure 12 is a detail view partially in section showing the means by which the driving pins for the paper displaces the stationary aligning pins from the paper, such latter pins being carried upon the upper portion of the paper roller supporting frame;

Figure 13 is a perspective showing the lock or stop for maintaining the pivoted cover plate in its open position.

Figure 14 is a plan view of one of the paper strips embodied in the invention.

Referring to the drawings in detail, 1 is a base of conventional style having a forward end plate 2 pivoted on the side walls 3 and 4 as at 5, and an end wall which is pivoted at 7 to the side walls 3 and 4.

The register is supplied with one or more rollers of paper called webs or sheets having a plurality of spaced apertures such as shown diagrammatically in Figure 14, where the apertures are located between the forms or tickets, are spaced inwardly from the margins of the paper, are arranged in pairs, between the tickets and are spaced from one another in pairs substantially the length of a ticket. These punched holes 9 in such a sheet 8 separated by the forms 10 are used both for the movement of the paper in the machine and for filing the separate tickets in loose leaf form in books according to the usual custom.

The rolls of paper in this machine for the purpose of illustration are designated 11, 12 and 13. They are mounted on spindles 14 journaled in slots 15 in side wall plates 16 which constitute the side walls of a detachable inwardly and outwardly sliding loading frame. This loading frame is joined together by suitable rods such as 17 at intervals.

The forward end of these side plates are projected into upwardly extending arms 18. These arms are provided with a series of spaced rollers or guide bars 19, 20 and 21, from which the sheets from the rollers 11, 12 and 13 are threaded. These sheets pass through a pair of spaced plates 22 and 23 carried on an overhanging arm 24 to the rear of the upwardly extending portions 18 of the loading frame. Beneath the plate 23 is pivoted on the pivot 25 an arm 26 which extends upwardly terminating in a plate 27 parallel with the direction of movement of the sheets of paper over the plate 23, which latter plate is slotted at 28 to receive the paper guide fingers 29 and is recessed at 30 to receive the stationary aligning pin 31. The aligning pins 31 are mounted on plates

27, and are yieldably maintained in position by springs 32, which have arms 33 engaging with arms 26, the other ends 34 engaging with the stationary under surface of the 5 plate 23.

Moving aligning pins 35 engage the pins 31 and push them out of engagement with the paper, taking the place of the pins 31. These pins 35 are carried upon the chain 36 10 which may be a chain or plate. It is preferable to have two pins on each plate and two plates on either side of the machine with the pins opposite to each other so that they travel together in transverse alignment in 15 pairs. As shown in Figure 1 these pins 35 are arranged in spaced relation and the distance between these pins is equal to the distance between each pair of openings 9 of the sheets 8. Prior to the start of the feeding 20 of the sheets through the machine the pins 31 engage beneath the sheets and are disposed between the adjacent openings so that those pins 35 already engaged with other openings 9 of the sheets 8 can move 25 the former without tearing them. By spacing the pins 35, as above stated, they will engage the pins 31 and force them from the openings 9 and enter the latter as each ticket is ejected on to the writing table.

The method of moving these chains or 30 plates is as follows. As shown the chains are mounted upon sprocket wheels 73 which in turn are located upon the roller shafts 38 journaled in the side walls of the register. 35 These sprockets are set in recesses 39 between raised rollers 40 on the main roller shaft 38 so that the chains are beneath the level of the rollers 40 which engage with the paper sheets. Thus the pins 35 project above the 40 surface of the rollers into the apertures of the paper, and frictional engagement is provided between the rollers 40 and the sheets of paper which are held in engagement therewith by the strips or fingers 29 which 45 are held in position on either side of the chain on the transverse supports 41.

It will be noted in Figure 12 the ends of the under guiding plate of the loading frame 50 extend into spaces between the rollers and the paper guide fingers 29, and that there is a relatively large space between the rollers and these guide plates at this point. It will be further observed upon examining Figure 55 1 that these spaces very materially decrease towards the rear of the machine so that the paper sheets are maintained more and more closely in engagement with the pins and rollers as the sheets progress to the rear of the machine and then proceed upwardly.

As soon as the paper sheets pass beneath 60 the chain and up over the rear end of the chain or plate and start upwardly they begin to travel over the inclined surfaces of the approach table which consists of a series 65 of spaced plates 42 separated by gaps 43

between which the pins are adapted to travel. These approach plates are at an angle to the writing table 44 to which they are joined, so it is thus possible to insure the gradual approach of the paper sheets and 70 very accurate guidance upon the approach table 44, from which they proceed beneath the register cover 45 until they pass between the ejecting rollers 46 and 47. This cover is cut away at 48 as usual to permit of writing upon the sheets carried above the writing table 44. The cover is also struck up into a semi-circular housing 49 to house the upper ejecting roller 47. It further accommodates the upwardly projecting lugs 50 which are slotted to receive the ends of the roller 47 to permit that roller to roll up and down to accommodate itself to various weights and sizes of paper.

It will be noted that these two rollers 46 and 47 are geared together by the gears 51 and 52. The roller 47 simply rests by its weight upon the sheets passing beneath it and between the roller 46.

The forward end of the cover terminates 90 in lugs or fingers 53 on either side thereof which are engaged with overhanging lugs 54 carried on the sliding cover plate 55 which encloses the forward part of the machine and which carries an inspection plate 56 of conventional design permitting the writing on the record sheets from the roller 13 to be examined at 57.

The gear 51 meshes with the gear 58 which is carried on the shaft 59. This gear 58 100 meshes with gears 67 and 74. The gear 67 drives gear 72 through the medium of meshing gears 68-71 inclusive, while the gear 74 drives gear 76 through the medium of gear 75. On this shaft 59 is a similar gear 60 which engages with the larger gear 61 carried on the shaft 62. On the shaft 62 is loosely mounted a gear 63 which is driven by the actuating gear or segment 64. This segment is mounted on the shaft 65 which in turn is actuated by the handle 66. Thus the 105 ejecting rollers are synchronized in their movement to a degree with the delivery mechanism delivering the paper on the writing table. From the same gear 60 is driven the gears 74 and 75 and 76, the last mentioned gear is carried on the record roll shaft 77 upon which is wound the record roll web 78. This web passes beneath and around the rollers or bars 79, 80 and 81 maintaining it 110 taut at all times.

In order to prevent the downward movement of the reciprocating handle in such a way as to permit of ejecting less than a whole ticket, there is secured to the shaft 62 (Fig. 10) a recessed cam portion 82 which extends about 180 degrees around the shaft 62. A shoulder 83 is provided at either end thereof one of which engages with the pawl 84 mounted on the gear 63 and spring pressed 125 130

into engagement with the low portion of this cam 85 by the spring 86, carried on the gear 63, which is loosely journaled on the shaft 62.

5 Thus unless the return stroke of the handle is carried to the minimum the pawl 84 will not be returned to position behind one of the shoulders 83, as shown in Fig. 10, in which position only the shaft 62 may be 10 rotated on the next operation of the handle. The handle is limited in its movement in one direction by the stop 87 and in the other direction it is necessary to make the full return stroke in order to bring it into operating 15 position. The member 66^a secured to gear segment 64 is at home-position when abutting against the stop-block 87 and at its furthest point of travel at the end of the paper feed when in contact with the hub 20 85 secured to the shaft 62, (Figure 1).

The usual carbon roll box 88 is provided with the carbon roll 89 having a plurality of carbon sheets, adapted to be interleaved transversely of the paper webs or sheets.

25 The cover 45 may be maintained in its uppermost position by the finger 90 which is pivoted on the inside of the side wall 3 on the pivot 91. It is maintained in locking engagement with the cover by the spring 92 30 which is connected to the free end 93 of the lever 90 and to the other end to a pin 94 carried on the inside of the wall 3.

The under side of the cover carries pairs of spaced bars depending therefrom marked 95 35 which engage with the upper surface of the paper on either side of the pins which travel between these depending bars.

Turning to the loading operation and the mechanism therefor it will be noted that the 40 rear end of the loading frame is carried on horizontal lateral guide ways or slides 96 upon which rests the cut off edge 97 of the lower rear corners of the side plates 16 of the loading frame. The forward ends of the 45 frame travel over the laterally inclined guide ways 98 on the surfaces 99, until they abut against the shoulders 100. Between the inclined guide ways 99 and the shoulders 100 is a cutout portion 101 in which rotates a 50 semi-circular rod 102, which is flush with the surface of 101 in one position and projects above it in another position when the rod is rotated. Upon being so rotated it lifts the lower forward corner of the said frames 16 55 lifting the forward end of the loading frame into operating position and until the frame assumes its uppermost position the machine will not operate. This is more fully shown in Figures 4 and 5 than in Figure 1 because 60 of the increased size of these figures.

This rod is operated by a finger piece on the machine marked 103.

It will be understood that I desire to comprehend within my invention such modifi-

cations as may be necessary to adapt it to 65 varying conditions of use.

Having thus fully described my invention, what I claim as new and desire to secure by Letters Patent, is:—

1. In an autographic register having a 70 writing table, means for supporting a plurality of rolls of paper from which sheets can be withdrawn, means to align said sheets progressively near the point of departure from the supply rolls, co-operating means 75 for disengaging the alining means from the sheets and drawing said sheets along to deliver the sheets upon the writing table.

2. In an autographic register having a 80 writing table, means for supporting a plurality of rolls of paper from which sheets can be withdrawn, means to align said sheets progressively near the point of departure from the supply rolls, cooperating means for 85 disengaging the alining means from the sheets and drawing said sheets along to deliver the latter to the writing table, and means for progressively moving said sheets onto the aligning means and moving means 90 and for maintaining them thereon.

3. In an autographic register, means for delivering sheets in aligned condition upon a writing table, a loading frame carrying a plurality of rolls of said sheets adapted to place the ends of the sheets in engagement with the aligning means, and aligning means carried by said loading frame for maintaining said sheets in aligned condition, said means being moved out of engagement with the sheets when the delivery means is 100 actuated.

4. In an autographic register having a writing table, a writing cover, means for supporting a plurality of rolls of paper, means for assembling the sheets from said 105 rolls in superimposed condition beneath the plane of said writing table, means traveling beneath said writing table adapted to engage with said sheets to align them and move them to the rear of and on top of said writing table and deliver them to said writing table beneath the cover of the machine in aligned condition, whereby the sheets travel beneath the writing table a distance over the end thereof and upon the table, and means to guide such sheets into engagement 110 with the aligning means and the delivery means until they pass over the table.

5. In an autographic register having a 120 writing table, a writing cover, means for supporting a plurality of rolls of paper, means for assembling the sheets from said rolls in superimposed condition beneath the plane of said writing table, means traveling beneath said writing table adapted to engage 125 with said sheets to align them and move them to the rear of and on top of said writing table and deliver them to said writing

- table beneath the cover of the machine in aligned condition, whereby the sheets travel beneath the writing table a distance over the end thereof and upon the table, and means 5 to guide such sheets into engagement with the aligning means and the delivery means until they pass over the table, and means cooperating with the sheets at the other end of the table for withdrawing the portion of 10 the sheets on the table therefrom. 6. In an autographic register having a writing table, means for supporting a plurality of paper rolls, a pair of spaced paper actuating rollers located beneath the plane 15 of the writing table, flexible means carried by said rollers adjacent either end of said rollers, spaced pins carried on said flexible means for aligning paper sheets, said flexible means being located beneath the surface 20 of said rollers, and means of delivering the paper sheets in superimposed condition adjacent one of said rollers so that the aligning pins may be inserted in the file punch holes in said paper to align the paper, and 25 means of maintaining said paper in engagement with the bottom of said rollers and said aligning means and of maintaining the paper in engagement with one of said rollers until it is delivered to the writing table, said 30 aligning means being so spaced that a pair thereof are always in engagement with said paper. 7. In an autographic register, having a writing table, means for supporting a plurality of paper rolls, a pair of spaced paper actuating rollers located beneath the plane 35 of the writing table, flexible means carried by said rollers adjacent either end of said rollers, spaced pins carried on said flexible means for aligning paper sheets, said flexible 40 means being located beneath the surface of said rollers, and means of delivering the paper sheets in superimposed condition adjacent one of said rollers so that the aligning pins may be inserted in the file punch holes in said paper to align the paper, and means of maintaining said paper in engagement 45 with the bottom of said rollers and said aligning means and of maintaining the paper in engagement with one of said rollers until it is delivered to the writing table, said aligning means being so spaced that a pair thereof are always in engagement with said paper, said means for maintaining 50 the paper in engagement with the aligning means and rollers being spaced at a greater distance at a point of first engagement of the paper with the aligning means than at the point where the paper is finally settled 55 upon the aligning means in aligned condition. 8. In an autographic register having a writing table, an approach table connected therewith at an angle thereto having a plurality of slots, spaced rollers, one of which 60 is located beneath the writing table and the other adjacent the end of the approach table, chains carried by said rollers adjacent either end thereof, aligning pins carried on said chains, said pins being arranged in pairs one 65 on either chain, said chains being located 70 75 80 85 90 95 100 105 110 115 120 125 130
- is located beneath the writing table and the other adjacent the end of the approach table, chains carried by said rollers adjacent either end thereof, aligning pins carried on said chains, said pins being arranged in pairs one on either chain, said chains being located beneath the surface of the rollers with the pins projecting above the surface of the rollers, sprockets carried on said rollers for actuating said chains positively, and means of maintaining a plurality of paper sheets in position to be engaged by the rollers to actuate them and to be engaged by the pins to align them, said means continuing from the point of first engagement with the paper with the rollers and pins to approximately the point of delivery of the superimposed sheets to the approach table, said sheets and chain passing through the slots in said approach table. 9. In an autographic register having a writing table, an approach table connected therewith at an angle thereto having a plurality of slots, spaced rollers, one of which is located beneath the writing table and the other adjacent the end of the approach table, chains carried by said rollers adjacent either end thereof, aligning pins carried on said chains, said pins being arranged in pairs one on either chain, said chains being located beneath the surface of the rollers with the pins projecting above the surface of the rollers, sprockets carried on said rollers for actuating said chains positively, and means of maintaining a plurality of paper sheets in position to be engaged by the rollers to actuate them and to be engaged by the pins to align them, said means continuing from the point of first engagement with the paper with the rollers and pins to approximately the point of delivery of the superimposed sheets to the approach table, said sheets and chain passing through the slots in said approach table, and means for removing the sheets from the writing table consisting of rollers geared to one another in front of the writing table, said upward roller being loosely mounted and resting by its weight upon the lower roller or the sheets therebetween, and means for driving said withdrawing rollers, paper delivery rollers and aligning means synchronously whereby the paper is fed and aligned by one agency to the writing table and those portions on the writing table withdrawn by another agency. 10. In an autographic register having a writing table, an approach table connected therewith at an angle thereto having a plurality of slots, spaced rollers, one of which is located beneath the writing table and the other adjacent the end of the approach table, chains carried by said rollers adjacent either end thereof, aligning pins carried on said chains, said pins being arranged in pairs one on either chain, said chains being located

beneath the surface of the rollers with the pins projecting above the surface of the rollers, sprockets carried on said rollers for actuating said chains positively, and means 5 of maintaining a plurality of paper sheets in position to be engaged by the rollers to actuate them and to be engaged by the pins to align them, said means continuing from the point of first engagement with the paper 10 with the rollers and pins to approximately the point of delivery of the superimposed sheets to the approach table, said sheets and chain passing through the slots in said approach table, and means for removing the 15 sheets from the writing table consisting of rollers geared to one another in front of the writing table, said upward roller being loosely mounted and resting by its weight upon the lower roller or the sheets therebetween, 20 and means for driving said withdrawing rollers, paper delivery rollers and aligning means synchronously whereby the paper is fed and aligned by one agency to the writing table and those portions on the writing 25 table withdrawn by another agency, and means actuated from the common source of power for winding one of said sheets withdrawn from the writing table within the register synchronously with the remainder 30 of the movements of the machine.

11. In an autographic register having a writing table, front and rear shafts located transversely of the register carrying driving rollers, sprockets spaced on said rollers 35 beneath the surface thereof, chains carried on said sprockets, pins arranged in pairs on said chains spaced the length of the tickets to be used in the register, a loading frame, means for supporting a plurality of 40 paper rolls on said loading frame, means of delivering superimposed sheets from said rolls rearwardly from the forward end of said frame adjacent the forward roll between rollers, and a paper guiding means 45 located therebetween and extending around the rear roller, said means consisting of a plurality of separated plates arranged in pairs on either side of the chains, spring 50 pressed aligning fingers carried by said loading frame adapted to be depressed by the pins on the chains when the pins pick up the superimposed sheets, means to engage 55 said sheets as they pass over the writing table, means to drive said paper actuating means, aligning means, and means for withdrawing the sheets from the writing table.

12. In an autographic register having a writing table, front and rear shafts located transversely of the register carrying driving 60 rollers, sprockets spaced on said rollers beneath the surface thereof, chains carried on said sprockets, pins arranged in pairs on said chains spaced the length of the tickets to be used in the register, a loading frame, means for supporting a plurality of paper

rolls on said loading frame, means of delivering superimposed sheets from said rolls rearwardly from the forward end of said frame adjacent the forward roll between said rollers, and a paper guiding means located 70 therebetween and extending around the rear roller, said means consisting of a plurality of separated plates arranged in pairs on either side of the chains, spring pressed aligning fingers carried by said loading 75 frame adapted to be depressed by the pins on the chains when the pins pick up the superimposed sheets, means to engage said sheets as they pass over the writing table, means to drive said paper actuating means, aligning means, and means for withdrawing the sheets from the writing table, said means consisting of a reciprocating handle, and ratchet means to insure that the handle 80 must be moved a full stroke before the sheets can be moved over the writing table and from said writing table.

13. In an autographic register having a writing table, front and rear shafts located transversely of the register carrying driving rollers, sprockets spaced on said rollers beneath the surface thereof, chains carried on said sprockets, pins arranged in pairs on said chains spaced the length of the tickets to be used in the register, a loading 90 frame, means for supporting a plurality of paper rolls on said loading frame, means of delivering superimposed sheets from said rolls rearwardly from the forward end of said frame adjacent the forward roll between said rollers, and a paper guiding means located therebetween and extending around the rear roller, said means consisting of a plurality of separated plates arranged in pairs on either side of the chains, spring 95 pressed aligning fingers carried by said loading frame adapted to be depressed by the pins on the chains when the pins pick up the superimposed sheets, means to engage said sheets as they pass over the writing table, means to drive said paper actuating means, aligning means, and means for withdrawing the sheets from the writing table, said loading frame being adapted to be moved out of the machine for loading and 100 alignment of the sheets, and means to control the elevation of said loading frame when in the machine which must be actuated before the paper sheets will be in position to be engaged by the paper actuating means and aligning means.

14. In an autographic register having a writing table, a loading frame having spaced side walls adapted to carry the spindles of paper, means at the forward end thereof for guiding upwardly and rearwardly in superimposed relationship sheets of paper from said roller, means mounted thereon for aligning said sheets projecting through the file punch apertures in said sheets, paper 125

- supporting means associated with said aligning and guiding means, rollers adapted to actuate said sheets, chains carried by said rollers and actuated thereby having spaced 5 pins in pairs for entering said file punch apertures in the sheets adapted to displace the stationary aligning means of the loading frame and take the place thereof in said file punch holes, the parts being so 10 arranged that the pins progressively are inserted further and further into said holes as the sheets pass beneath said chains and said paper guides approach closer and closer to said chains towards the rear thereof.
15. In a means for delivering paper onto a writing table in an autographic register, a writing table, a cover having spaced depending ledges arranged in pairs spaced from one another, actuating rollers, flexible means actuated thereby connecting said rollers and located beneath the surface of said rollers, aligning pins carried in pairs on said flexible means projecting above the surface of said rollers and into the space between said 20 ledges, whereby paper sheets are actuated by the surface of said rollers, aligned by said pins and are maintained in engagement with said rollers and said pins by engaging with the under surface of said depending ledges.
25. 16. In a means for delivering paper onto a writing table in an autographic register, a writing table, a cover having spaced depending ledges arranged in pairs spaced from one another, actuating rollers, flexible means actuated thereby connecting said rollers and located beneath the surface of said rollers, aligning pins carried in pairs on said flexible means projecting above the surface of said rollers and into the space be- 30
35. tween said ledges, whereby paper sheets are actuated by the surface of said rollers, aligned by said pins and are maintained in engagement with said rollers and said pins by engaging with the under surface of said depending ledges, and pairs of parallel spaced plates adjacent said roller surfaces and parallel with said flexible member, maintaining the paper sheets against said rollers and pins on the under side of the 40 flexible member and rollers, said pins projecting between said plates.
45. 17. In an autographic register, means for delivering paper to a writing table, a loading frame carrying rolls of paper, and means for elevating the forward end of said loading frame to bring it into operating position so that the sheets from the rollers may be 50 inserted into the feeding means.
55. 18. In an autographic register, means for delivering paper to a writing table, a loading frame carrying rolls of paper, means for elevating the forward end of said loading frame to bring it into operating position so that the sheets from the rollers may be 55 inserted into the feeding means, said elevating means consisting of a cam rod engaging the forward end of said frame and means on said register for actuating said rod.
60. 19. In an autographic register, a loading frame carrying supply rolls of paper, and means within said register for maintaining said frame in a tilted position to bring its forward end adjacent to a paper aligning and actuating means.
65. 20. In an autographic register, a loading frame carrying supply rolls of paper, means within said register for maintaining said frame in a tilted position to bring its forward end adjacent to a paper aligning and actuating means, and means associated with the forward end of said loading frame for giving it a predetermined degree of additional elevation to bring it into operating 70 position.
75. 21. In an autographic register, a casing, means for mounting a plurality of longitudinally movable sheets and feeding them through the casing, longitudinally movable paper alining means actuated by the means for mounting and feeding the sheets, and pivoted alining means mounted in the casing and arranged in advance of the longitudinally movable alining means and adapted to be moved out of engagement from the paper upon the approach of the longitudinally movable alining means to the paper sheets.
80. 22. The combination with a casing and means for feeding a plurality of superimposed sheets longitudinally through the casing, of a plurality of pivoted paper sheet alining elements normally urged into engagement with the paper sheets, and longitudinally movable paper alining means arranged to intermittently disengage the pivoted alining elements from the paper and engage the latter.
85. 23. The combination with a casing, and means for feeding a plurality of superimposed sheets in a longitudinal direction, a horizontally arranged approach table arranged at the top of the casing and over which the sheets are adapted to pass, and a plurality of angularly disposed spaced guide plates carried by the approach table, and longitudinally movable means adapted to engage the paper sheets as the same are being moved through the guide plates.
90. In testimony whereof, I affix my signature.
100. PHILIP A. JACKSON.
